ENCLOSED ELECTRIC DEVICE

Hermon L. Van Valkenburg, Wauwatosa, Wis.,
assignor to Square D Company, Detroit, Mich.,
a corporation of Michigan

Application April 5, 1937, Serial No. 135,014

13 Claims. (Cl. 174—52)

This invention relates to electric circuit controlling instrumentalities and more particularly to mounting and enclosing means therefor.

One object of the invention is to provide a 5 mounting means for an electric circuit controlling instrumentality which shall provide for normal relatively rigid support on the back wall of the enclosing box and which shall also provide for supported movement to the exterior of the box 10 to uncover the box interior for manipulation.

Another object of the invention is to provide a 15 mounting means for an electric instrumentality which shall be relatively rigid in its enclosed interior position and which may be readily moved to a supported exterior position and in its exterior position be readily detachable from its enclosure.

Another object of the invention is to provide a 20 mounting for an electric circuit controlling instrumentality which shall provide for sliding and swinging movement relative to its enclosure into a position exterior thereof and which provides for detachment of the instrumentality while it is in its exterior position.

25 Other objects and features of the invention will be readily apparent to those skilled in the art from the following specification and the appended drawings illustrating certain preferred embodiments of the invention in which:

30 Figure 1 is a front elevational view of the assembly according to the present invention with the front cover opened and partially broken away.

Figure 2 is an enlarged partial sectional view on 35 the line II—II of Figure 1.

Figure 3 is a view similar to Figure 1 with the parts enlarged and in part broken away and with the front cover not shown.

Figure 4 is a vertical sectional view on a small 40 er scale on the line IV—IV of Figure 3.

Figure 5 is a partial horizontal sectional view showing the unit moved to its exterior position.

Figure 6 is a vertical sectional view showing the manner in which the instrumentality is detached 45 from the enclosing box.

Figure 7 is a horizontal view, partly in section, of a modified form of mounting means with a moving position shown in dotted lines.

Figure 8 is a vertical sectional view taken on 50 the line VIII—VIII of Figure 7.

The assembly according to the present invention comprises an outer enclosing box 1 having an openable cover 2 which may be hingedly mounted thereon. Within the box is disposed an electric circuit controlling instrumentality which, as here

shown, comprises an electromagnetic switch generally indicated at 3 and which may take the form shown in the co-pending application of Josef Bierenfeld and Lawrence G. Maechtl, Serial No. 97,532, filed August 24, 1936, for Electric switches. 5 This instrumentality has its various parts mounted on a metallic backing plate 4 which may be rigidly secured to the back of the box 1 by means of studs 5 threaded into spacers 6 attached to the back wall of the box. Rigidly secured to the back plate 4 as by means of studs 7 is a supporting plate 8 adapted to carry the switch when the studs 5 are removed. The primary function of the spacers 6 is to provide a wiring space between the back of the box and the plates 4 and 8 and in 10 addition to provide clearance for the plate 8 and the studs 7. The supporting plate 3 may take any form desired and is shown as a truncated inverted triangle to clear the two lower studs 5 and may have its upper base notched to provide 15 clearance for the stud 5 at the upper left hand corner of the back plate 4. Mounted on the side wall of the box are a pair of spaced S-shaped angle members 9 and 11 which may be connected to the side wall of the box in any manner and 20 are here shown as attached by studs 12. This construction results in a pair of vertical legs 13 and 14 extending the depth of the box in spaced relation to the side wall thereof. The legs 13 and 14 are bent over in the front of the box and 25 extended to the side wall as at 15 and 16. The front portions 15 and 16 adjacent to the side wall are provided with notches at their upper edges as at 17 and 18. The upper edges of the legs 13 and 14 adjacent to the back wall of the 30 box are similarly provided with notches 19 and 21. The plate 8 is provided with suitable notches adjacent its top and bottom edges adapted to co-operate with the angle members 9 and 11. The lower edge is provided with a simple notch 22 engageable with and guided by the top edge of the leg 14. The side of the plate 8 adjacent its upper edge is provided with a somewhat L-shaped notch 23 adapted to interlock with the leg 13 on the bracket 9. An additional shallow notch 24 may 35 be provided to give clearance to the supporting leg of the bracket 9.

The operation of the assembly will now be described. As shown in Figures 1 to 4 inclusive the parts are in their normal operating position with the circuit instrumentality rigidly mounted on the back wall of the box by studs 5 and spacers 6. In the operation of drawing in of circuit wires and for other operations it may become desirable to clear the interior of the cabinet to make it 40 45 50 55 60 65

more readily accessible. For this purpose the studs 5 are removed whereupon the support of the instrumentality and its back plate 6 will be transferred to the supporting plate 8. This will now normally be maintained in the interior position due to the engagement of the top edges of the notches 22 and 23 in the notches 16 and 17 respectively. The supporting assembly is then raised slightly to disable the interlocking notches whereupon the entire assembly may be readily slid forward with the plate 8 and its associated parts supported by the angle members 9 and 11. Upon reaching the front of the box in this sliding movement the supporting parts may then be readily rotated through an angle of 90° into the position shown in Figure 5 which is again a stable position due to the locking of notches 22 and 23 with the notches 16 and 17 respectively. In this position the interior of the box is cleared for any purpose which may be desired and at the same time the circuit controlling instrumentality will be maintained in supported relation on the box. To again place the instrumentality within the box the movements are the exact reverse of those heretofore described.

For replacement and for repair and other purposes which cannot be achieved with facility while the circuit controlling instrumentality is supported on the box provision is made for readily detaching the supported parts and this is more clearly illustrated in Figure 6. In the swung-out position of Figure 5 the plate 8 and its supported parts are raised upwardly until the notch 22 clears the front portion 15 on the angle member 11 and the lower edge of the plate 8 is swung forwardly as shown in dotted lines in Figure 6 whereupon the front portion 15 on the angle 9 may be disengaged from the L-shaped notch 23 by again raising the plate 8. This permits the supporting plate and the instrumentality supported thereon to be entirely detached from the box. In again connecting the parts the notch 23 again receives the front portion 15 on the angle 9 while the plate is in the tilted position shown in dotted lines in Figure 6 whereupon the lower end is swung inwardly and the slight raising of the plate permits the notch 22 to be again engaged with the portion 16 on the angle 11. The plate 8 may then be rotated back into its front position parallel to the back of the box and thereupon the entire assembly may be slid backward into the interior position of the switch which may then be rigidly connected to the back wall of the box by screwing the studs 5 into the spacer 6. It is to be noted that the plate 8 can be removed from the box only when in its exterior swung-out position as in Figures 5 and 6 and that at all other times it will be interlocked with the angles 9 and 11. This permits ready sliding and rotat-

ing movement to the exterior of the box without danger of the supported parts becoming detached of themselves and falling with possible attendant injury. On the other hand, while in its exterior position, a very simple procedure permits the entire detachment and removal of the instrumentality from supported relation with the box. The construction is simple and rigid and due to the final connection of the backing plate to the back of the box permits the support of relatively heavy instrumentalities where vibration is undesirable.

In the modification illustrated in Figures 7 and 8 there is shown an outer enclosing box 31 provided with an openable cover, not shown, and on the back wall of which are rigidly mounted spacer

elements 32 interiorly threaded to receive studs 33 which rigidly mount a metallic backing and supporting plate 34 upon which an electric circuit controlling instrumentality, not shown, is mounted. The studs 33 are provided with fibre washers 35 to prevent the falling out of the studs when loosened and the spacers 32 are countersunk, as shown, to provide clearance for the ends of the stud in the interior movement of the instrumentality. To the plate 34 is rigidly secured, as by means of studs 35, a bracket 36 which is provided adjacent the left hand side wall of the box with enlarged openings 37 which receive strap portions 38 rigidly secured to the side wall of the box by riveting or welding. The openings 37 are considerably larger than the straps 38 to provide for easy swinging movement of the instrumentality and also to provide lost motion or play to permit the easy alignment of the studs 33 with the spacer 32. The operation of this form of mounting is readily apparent. As shown in Figure 7, it is in its interior position with the circuit controlling instrumentality rigidly supported on the back wall of the box through the studs 33. When these studs are loosened the backing plate 34 and the circuit controlling instrumentality carried thereby may be swung, as shown in dotted lines, to the exterior of the box upon the hinges formed by the engagement between the bracket 36 and the straps 38. To entirely remove the circuit instrumentality from supported relation with the box the studs 35 may be removed and the plate 34 and the instrumentality mounted thereon entirely separated from the box for replacement and repair. This construction provides for easy swinging movement of the instrumentality to the box exterior to facilitate the drawing in of circuit wires and the connection of conduit and at the same time provides for rigid mounting of the instrumentality in its interior position independent of the hinge mounting arrangement.

While certain preferred embodiments of the invention have been specifically disclosed, it is understood that the invention is not limited thereto as many variations will be readily apparent to those skilled in the art and the invention is to be given its broadest possible interpretation within the terms of the following claims.

What is claimed is:

1. Supporting and enclosing means for an electric circuit controlling switch comprising an enclosing box having an openable cover, an electric circuit controlling switch within said box, means mounting said switch for movement to the exterior of the box while supported on the box to expose the box interior to facilitate operations therein, and means in addition to said mounting means for rigidly supporting said switch on the back wall of the box in its interior position, said cover being independently openable without disturbing said switch support.

2. Supporting and enclosing means for an electric circuit controlling switch comprising an enclosing box having an openable cover, an electric circuit controlling switch within said box, means mounting said switch for swinging movement to the exterior of the box to expose the box interior to facilitate operations therein while supporting the switch from a side wall of the box, and means in addition to said mounting means for rigidly supporting said switch from the back wall of the box in its interior position, said cover being independently openable without disturbing said switch support.

3. Supporting and enclosing means for an electric circuit controlling switch comprising an enclosing box having an openable cover, an electric circuit controlling switch within said box, means to be slid to the front of the box and thereafter rotated into a supported position on said front portions thereby uncovering the interior of the box while maintaining the instrumentality in supported position on the box. 5

5. Supporting and enclosing means for an electric circuit controlling switch comprising an enclosing box having an openable cover, a pair of S-shaped angle members mounted in vertically spaced relation upon an interior side wall of the box and extending for the depth of the box with front portions bridging the spaces between the free legs of the S and the side wall of the box, a supporting plate slidably engageable with the free legs on said angles, an electric circuit controlling instrumentality mounted on said plate, means for rigidly securing said instrumentality to the back of the box, release of said securing means permitting said plate and instrumentality to be slid to the front of the box and thereafter rotated into a supported position on said front portions hereby exposing the interior of the box to facilitate operations therein while supporting the instrumentality at the box exterior. 10 15 20

4. Supporting and enclosing means for an electric circuit controlling switch comprising an enclosing box having an openable cover, an electric circuit controlling switch within said box, and cooperating means mounted on said box and connected to said switch providing for sliding movement of said switch to the front of the box and for swinging movement thereafter to the exterior of the box to expose the box interior to facilitate operations therein while supporting the switch on the box, and means in addition to said last mentioned means for rigidly supporting said switch on the back wall of the box in its interior position, said cover being independently openable without disturbing said switch support. 25 30

5. Supporting and enclosing means for an electric circuit controlling switch comprising an enclosing box having an openable cover, a mounting plate in said box, an electric switch mounted on said plate, and means on a side wall of the box supporting said plate and providing for sliding movement thereof to the front of the box and for swinging movement thereafter to the exterior of the box to uncover the box interior while supporting the switch on the box, and means in addition to said last mentioned means for rigidly supporting said plate on the back wall of the box in its interior position, said cover being independently openable without disturbing said plate support. 35 40 45

6. Supporting and enclosing means for an electric circuit controlling switch comprising an enclosing box having an openable cover, an electric circuit controlling switch within said box, and cooperating means mounted on said box and connected to said switch providing for sliding movement of said switch to the front of the box and for swinging movement thereafter to the exterior of the box to expose the box interior to facilitate operations therein while supporting the switch on the box, said cooperating means providing for detachment of said switch from the box when in its exterior position, and means in addition to said last mentioned means for rigidly supporting said switch on the back wall of the box in its interior position, said cover being independently openable without disturbing said switch support. 50 55

7. Supporting and enclosing means for an electric circuit controlling instrumentality comprising an enclosing box having an openable cover, a pair of vertically spaced members supported on a side wall of the box and having vertical portions parallel to and spaced from said box wall and front portions extending to the box wall, a mounting plate supported on said vertical portions, an electric circuit controlling instrumentality mounted on said plate, means maintaining said plate within the enclosing box, release of said retaining means permitting said plate and the instrumentality mounted thereon

70 75

8. Supporting and enclosing means for an electric circuit controlling instrumentality comprising an enclosing box having an openable cover, a pair of S-shaped angle members mounted in vertically spaced relation upon an interior side wall of the box and extending for the depth of the box with front portions bridging the spaces between the free legs of the S and the side wall of the box, a supporting plate slidably engageable with the free legs on said angles, an electric circuit controlling instrumentality mounted on said plate, means for rigidly securing said instrumentality to the back of the box, release of said securing means permitting said plate and instrumentality to be slid to the front of the box and thereafter rotated into a supported position on said front portions hereby exposing the interior of the box to facilitate operations therein while supporting the instrumentality at the box exterior, and inter-engaging parts on said legs and plate providing for ready detachment of the supporting plate and instrumentality from the box in its exterior position only. 80 85

9. Supporting and enclosing means for an electric circuit controlling instrumentality comprising an enclosing box having an openable cover, a pair of vertically spaced members supported on a side wall of the box and having vertical portions parallel to and spaced from said box wall and front portions extending to the box wall, a mounting plate supported on said vertical portions, an electric circuit controlling instrumentality mounted on said plate, means maintaining said plate within the enclosing box, release of said retaining means permitting said plate and the instrumentality mounted thereon

said plate to be slid to the front of the box, rounded front portions on said members providing for swinging movement of the plate to the box exterior, and cooperating parts on said members 5 and plate permitting ready removal of the plate in its exterior position.

12. Supporting and enclosing means for an electric circuit controlling switch comprising an enclosing box having an openable cover, an electric circuit controlling switch, means rigidly mounting said switch on the back wall of the box, and a bracket connected to said switch and having a hinged connection on said box distinct from said back mounting means to provide for supported swinging movement of said switch to the box exterior when said mounting means is released, said cover being independently openable without disturbing said switch mounting.

13. Supporting and enclosing means for an electric circuit controlling switch comprising an enclosing box having an openable cover, an electric circuit controlling switch, means rigidly mounting said switch on the back wall of the box, and a bracket connected to said switch and having a hinged connection on said box distinct from said back mounting means to provide for supported swinging movement of said switch to the box exterior when said mounting means is released, said hinged connection providing for limited movement of said bracket relative to the box to facilitate the application of said mounting means in the interior position of the switch, said cover being independently openable without disturbing said switch mounting.

HERMON L. VAN VALKENBURG.
